To all whom it may concern:

Be it known that I, Ferdinand Armbrust, a citizen of the United States, residing at Hoxsie, State of Rhode Island, have invented a new, original, and ornamental Design for a Link for a Jewelry Chain, of which the following is a specification, reference being had to the accompanying drawing, forming a part hereof.

In the drawing:

Fig. 1 is a top plan view of a link for a jewelry chain, illustrating the new design;

Fig. 2 is an enlarged end view thereof;

Fig. 3 is a side view of Fig. 1; and
Fig. 4 is an enlarged detail central section on the line 4—4 of Fig. 1, showing the angular formation of the vertically ribbed sections.

I claim:

The ornamental design for a link for a jewelry chain, as shown.
